Primary Examiner — Cynthia Ramirez*Assistant Examiner* — Michael A Maharajh(74) *Attorney, Agent, or Firm* — Howard IP Law Group(57) **CLAIM**

The ornamental designs for an eye massager, device as shown and described.

DESCRIPTION

FIG. 1 is a front view of the eye massager;

FIG. 2 is a rear view of the eye massager;

FIG. 3 is a left side view of the eye massager;

FIG. 4 is a right side view of the eye massager;

FIG. 5 is a top view of the eye massager;

FIG. 6 is a bottom view of the eye massager;

FIG. 7 is a first perspective view of the eye massager;

FIG. 8 is a second perspective view of the eye massager; and,

FIG. 9 is a reference view of the eye massager that is in usable condition.

The broken lines shown in the drawings are for the purposes of illustrating environmental structure, which form no part of the claimed design.
